[57] ABSTRACT

An IMPATT diode having four conducting regions. The relationship between the two center conducting regions in both thickness and carrier concentration are chosen such that breakdown voltage equals punch-through voltage. By controlling the carrier concentration between these two regions, the efficiency of the IMPATT diode is improved.

IMPATT DIODE

BACKGROUND OF THE INVENTION

The invention herein disclosed was made in the course of or under a contract or subcontract thereunder with the Department of the Army.

The present invention relates to an IMPATT diode having improved efficiency at its desired operating frequency.

The IMPATT diode is used as a microwave power source. By reverse biasing an IMPATT diode, the resulting avalanche and transit time cause a high frequency negative resistance. That is to say, the physical structure of the IMPATT diode, when reverse biased, causes a phase differential of 180° between the output voltage and the output current. The microwave negative resistance makes possible high frequency power amplification or oscillation, depending on the type of circuit that makes use of the IMPATT diode.

It is desirable to have the IMPATT diode operate with its breakdown voltage equal to its punch-through voltage. When operating under such conditions, there is little chance for a premature burnout or excess loss of power.

The direct current (dc) to high frequency (rf) conversion efficiency of an IMPATT diode is dependent on the ratio of the carrier concentration of the two center N-type subregions. It is desirable to control these carrier concentrations in order to improve IMPATT diode efficiency.

SUMMARY OF THE INVENTION

A semiconductor diode comprising a body of single crystalline semiconductor material having a region of P-type conductivity and a region of an N-type conductivity, with a PN junction therebetween. The N-type region is divided into three subregions. The carrier concentration and thickness of the center subregion is in such relationship to the carrier concentration and thickness of the subregion contiguous to the PN junction, that the punch-through voltage equals the breakdown voltage at the operating frequency of the diode.

BRIEF DESCRIPTION OF THE DRAWINGS

FIG. 1 is a cross-sectional view of the IMPATT diode of the present invention.

FIG. 2 is a graphical representation of the electrical field to the power law.

FIG. 3 is a family of curves representing the operating efficiency to the ratio of carrier concentration for specific values of the power law.

THE PREFERRED EMBODIMENT STRUCTURE

Referring to FIG. 1, the present embodiment of the IMPATT diode is designated as 10. The IMPATT diode 10 comprises a body of single crystalline semiconductor material, such as silicon, gallium arsenide and the like, having two regions of opposite conductivity, designated 12 and 14. Region 12 is of a P-type conductivity, with a high carrier concentration, that forms a PN junction 13, with the region 14, which is of N-type conductivity. Region 12, of the present embodiment of the IMPATT diode, can be replaced by a Schottky barrier with no change in results. N-type conductive region 14 includes three subregions, designated 16, 18 and 20, which vary in carrier concentration and thickness. Sub-

region 16 is of a high carrier concentration and only functions as an electrical contact.

Subregions 18 and 20 are critical in that the proper relationship between their respective carrier concentrations and widths result in the punch-through voltage being nearly equal to the breakdown voltage. Punch-through voltage is that voltage for which the depletion layer in the reverse-biased PN junction spreads sufficiently to make electrical contact with the junction at 10 the interface of subregions 16 and 18. Breakdown voltage is defined as the reverse bias voltage needed to cause a reverse current flow due to avalanching. When the punch-through voltage equals the breakdown voltage, the IMPATT diode operates at a higher efficiency with less of a possibility of a premature burnout.

The carrier concentration n_1 , and width l_1 , of subregion 20 and the carrier concentration n_2 and width l_2 of subregion 18 are determined as follows:

The width l_2 of subregion 18 is determined by the 20 equation:

$$l_2 = (v_s/2f) \quad (1)$$

where v_s is the known saturation velocity of electrons for the particular semiconductor material used, and f is the frequency at which the IMPATT diode 10 will be operating. With v_s and f known, the width l_2 is calculated by equation (1).

Carrier concentration n_2 of subregion 18 can be determined by the following equation:

$$n_2 = \frac{1}{2} (E_c^2 \epsilon / V_B e) \quad (2)$$

where V_B is the semiconductor breakdown voltage, E_c is the critical electric field, e is the electron charge, and ϵ is the dielectric constant.

The above relationship is graphically represented in the article by T. Misawa, "Microwave Silicon Avalanche Diode With Nearly-Abrupt-Type Junction," IEEE TRANSACTIONS ON ELECTRON DEVICES, Vol. ED-14, Sept. 1967, page 582. Thus, carrier concentration n_2 can be calculated by equation (2) or more conveniently by the Misawa graph.

Once n_2 is known, n_1 is determined by using the following formula:

$$n_1 = \{[(2\pi\eta m_2 + \pi\eta + 1)n_2] / [m_2^2(1 - \pi\eta)]\} \quad (3)$$

where η is the operating efficiency and m_2 is the power law for subregion 18. Operating efficiency of the IMPATT diode 10 is selected for the particular design requirement, usually about 30. Power law m_2 is a function of the critical electric field, E_c , and is calculated by:

$$m = 2 [(6.85 \times 10^5) / E_c]^2 \quad (4)$$

The value of critical electric field, E_c , for a particular carrier concentration has been previously ascertained and this relationship is graphically shown in a book by H. A. Watson, MICROWAVE SEMICONDUCTOR DEVICE AND THEIR CIRCUIT APPLICATION, 1969, Page 124. As a designing rule of thumb, since E_c is a slow varying function of n_1 , the value of n_2 , which

is known from the Watson graph, can be used to determine the value of E_c . Once E_c is determined, it is substituted into equation (4), and m_2 can thus be calculated from equation (4).

For convenience, equation (4) has been plotted as FIG. 2, thus by ascertaining the critical electric field, E_c , the power law m_2 can be taken from this graph.

FIG. 3 is a graphical representation of operating efficiency, η , to the ratio of carrier concentration, (n_1/n_2) , for specific values of m_2 . Once the operating efficiency has been selected and m_2 is known from FIG. 2, FIG. 3 yields the ratio (n_1/n_2) , from which n_1 is determined since n_2 has been ascertained from either equation (2) or the Misawa graph. Thus, FIG. 3 is the graphical representation of equation (3).

The last design value to be determined is l_1 , which is ascertained by the following equation:

$$l_1 = \{E_c / [(m_1 + 1) (n_1 e / \epsilon)]\}$$

(5) 20

where e is the electron charge and ϵ is the dielectric constant. Both e and ϵ are constants which are known, ϵ is a different constant for each specific semiconductor material. E_c has been determined, and since n_1 has been calculated, then FIG. 2 yields the value of m_1 . With E_c and m_1 known, l_1 is calculated from equation (5).

With n_1 , n_2 , l_1 and l_2 known, the design of the $P^+ - n - n^+$ IMPATT diode structure is completed. The following is a design example for the $P^+ - n^+ - n - n^+$ IMPATT diode structure of GaAs, at an operating frequency of 10 GHz.

From equation 1:

$$l_2 = (v_s/2f)$$

where

$$v_s = 1 \times 10^7 \text{ cm/sec for GaAs}$$

thus

$$l_2 = 5 \text{ microns.}$$

With l_2 known, n_2 is determined from equation (2) or more conveniently from the Misawa graph which yields:

$$n_2 = 6 \times 10^{15} \text{ cm}^{-3}.$$

Referring to the Watson graph, with $n_2 = 6 \times 10^{15} \text{ cm}^{-3}$ for GaAs

$$E_c = 4.50 \times 10^5 \text{ v/cm.}$$

Once E_c is known, FIG. 2 yields m_2 which in this design example is equal to 4.6. If an operating efficiency, η , of 30 percent is selected, FIG. 3 indicates for $m_2 = 4.6$ the ratio $(n_1/n_2) = 10$. Since n_2 equals $6 \times 10^{15} \text{ cm}^{-3}$, n_1 must equal $6 \times 10^{16} \text{ cm}^{-3}$.

The value of l_1 is determined from equation (5). The constants e and ϵ for GaAs equal 1.6×10^{-19} coulombs and 110.6×10^{-12} farads/meter respectively. With n_1 equal to $6 \times 10^{16} \text{ cm}^{-3}$, E_c equals $5.5 \times 10^5 \text{ v/cm}$ from the Watson graph, and with E_c known, FIG. 2 yields m_1 equal to 3. Substituting all the known values into equation (5) yields:

$$l_1 = 0.16 \text{ micron.}$$

For the ordinary $P^+ - n - n^+$ IMPATT diode structure,

where n_1/n_2 equals 1, the theoretical efficiency for $m = 6$ is approximately 23 percent. The embodiment of the present IMPATT diode with (n_1/n_2) equal to 10 has an efficiency of 30 percent. The improvement in efficiency is even more dramatic for high frequency IMPATT diodes which have high carrier concentrations in the n region and thus smaller values of m .

I claim:

1. A semiconductor diode comprising a body of single crystalline semiconductor material having a region of P-type conductivity and a region of an N-type conductivity, with a PN junction therebetween, said N-type region being divided into first, second and third subregions of which the second subregion is a center subregion doped to have a carrier concentration, n_2 , substantially exceeding intrinsic carrier concentration, and the subregion contiguous to said PN junction is said first subregion doped to have a predetermined carrier concentration, n_1 , greater than said center subregion carrier concentration, said third subregion being doped to have a carrier concentration substantially greater than said center subregion, said center subregion having a thickness, l_2 , and said subregion contiguous to said PN junction having a thickness, l_1 , less than said thickness, l_2 , so that diode punch-through voltage to said third subregion substantially equals diode breakdown voltage at a desired diode operating frequency.

2. The semiconductor diode in accordance with claim 1 in which the center subregion carrier concentration is determined by $n_2 = \frac{1}{2} (E_c^2 \epsilon / V_B e)$ where E_c is the diode critical electric field, V_B is the diode breakdown voltage, e is the electron charge and ϵ is the dielectric constant of said semiconductor material, and said N-type subregion contiguous to said PN junction has a carrier concentration $n_1 = [(2\pi\eta m_2 + \mu\eta + 1) / (1 - \pi\eta)(n_2/m_2^2)]$ where η is the selected operating efficiency and m_2 is equal to $[2 \times (6.85 \times 10^5 / E_c)]^2 (6.85 \times 10^5 / E_c)^2$, and said N-type subregion contiguous to the PN junction has a thickness determined by $\{l_1 = [E_c / (m_1 + 1) (n_1 e / \epsilon_1)]\} l_1 = [E_c / (m_1 + 1) (n_1 e / \epsilon)]$ where m_1 substantially equals m_2 .

3. The semiconductor diode in accordance with claim 1 where the operating frequency is between 1 and 100 GHz.

4. A semiconductor diode comprising a body of crystalline semiconductor material having a region of N-type conductivity with a Schottky barrier contact, said N-type region being divided into first, second and third subregions of which the second subregion is a center subregion doped to have a carrier concentration, n_2 , substantially exceeding intrinsic carrier concentration, and the subregion contiguous to said Schottky barrier is said first subregion doped to have a predetermined carrier concentration, n_1 , greater than said center subregion carrier concentration, said third subregion being doped to have a carrier concentration substantially greater than said center subregion, said center subregion having a thickness, l_2 , and said subregion contiguous to said Schottky barrier contact having a thickness, l_1 , less than said thickness, l_2 , so that diode punch-through voltage to said third subregion substantially equals diode breakdown voltage at a desired diode operating frequency.
